UNITED STATES PATENT OFFICE.

CHARLES AUGUSTUS PEASLEY AND ISAAC F. DODGE, OF GOWEN, MICHIGAN.

HAY-RACK.

SPECIFICATION forming part of Letters Patent No. 297,842, dated April 29, 1884.

Application filed October 6, 1883. (No model.)

To all whom it may concern:

Be it known that we, CHARLES A. PEASLEY and ISAAC F. DODGE, citizens of the United States of America, residing at Gowen, in the county of Montcalm and State of Michigan, 5 have invented certain new and useful Improvements in Hay-Racks; and we do hereby declare the following to be a full, clear, and exact description of the invention, such as will 10 enable others skilled in the art to which it app pertains to make and use the same, reference being had to the accompanying drawings, and to letters or figures of reference marked thereon, which form a part of this specification.

15 This invention relates to certain new and useful improvements in attachments for farm-wagons, its object being to provide a means for carrying hay, straw, and other light produce from place to place, and in the construction 20 of a frame which can be folded and laid away in small space; and our invention consists in the construction and combination of the parts, as will be hereinafter more fully set forth and illustrated.

25 In the accompanying drawings, which illustrate our invention, Figure 1 is a perspective view, showing our improved apparatus arranged upon a wagon. Fig. 2 is a detailed view of the binder-pole, and Fig. 3 is a view 30 of the clamp.

In the accompanying drawings, A represents a farm-wagon of ordinary construction, which is adapted to receive the rack B B, the end cross-bars of this rack being provided with a 35 pulley, b. The front and rear end-gates of the wagon are provided with uprights or posts C and D, which are secured to the same in the ordinary manner. The front post, C, is provided with a longitudinal recess or slot, c, 40 having transverse bars which are located within the slot, as shown in Fig. 1 of the accompanying drawings. It is also provided at the top with a suitably-constructed hook, over which may be placed the reins, so that they 45 will be out of the way when the wagon is being loaded. This hook also serves the purpose of suspending two sections of the binding-pole, so as to leave it within easy reach when the wagon is loaded. The rear post, D, which is 50 preferably of less length than the front post, is provided at its upper end with a cleat, d,

by means of which the rear section of the binding-pole may be attached to the same.

The binder-pole is composed of three or more sections, E E' E''. The front section, E, 55 has at its front end a hook, e, and at its rear end is provided a socket, e', to the rear of which is pivoted a link, F, which engages with the hook f, located on the upper side of the adjacent portion of the binder-pole E, the front 60 end of which is reduced in size and provided with shoulders, so that its end may enter the socket e'. This binder-pole is provided with two or more similar joints, and the last section of the same is of sufficient length to extend over the rear end of the wagon-body. By thus joining the binding-pole the same may be easily handled and taken apart, and the links and hooks located upon the upper side of the same will hold the parts securely 70 together when a downward pressure is exerted at the ends.

When the wagon is loaded and the binder-pole placed in position, we secure to the same a clamp, G, which consists of two members, g g', 75 which are pivoted to each other at their lower portion, as shown at h. Each of these members is provided, at a point above the pivot h, with a perforation, h', within which are secured the ends of the cord H. This clamp is 80 also provided above its pivoted portion with semicircular openings i, which are of about the same size as the binding-pole, so that when the clamp is closed, as shown in full lines in Fig. 3, the parts will be secured to each other. 85 The upper part of the member g of this clamp G is wedge-shaped, and the opposite member, g', is provided with a slot, k, which extends obliquely from the upper part of the member g' to near the clamping-jaws i. Within this slot 90 is secured a suitable link, k'. When the wagon is loaded, the ropes H, which extend under the pulleys b, are tightened, and the free ends may be either passed around the cleat d and secured to the wagon-body, or they may be 95 tied around the upper part of the clamp G, as shown in the accompanying drawings, which is desirable when they are made fast by the person on top of the wagon.

The cleat d may be provided on its inner 10 portion, adjacent to the post D, with a roller, over which the ropes H may pass.

- The end of the binder-pole may be provided with a chain and ring, so that a person upon the ground may assist in drawing the same downwardly, or holding the same in position 5 while the ropes are being tied. The ring at the end of this chain may also be passed over the hook on the front binding-post when it is desirable to suspend this section of the binder-pole at the front of the wagon.
- 10 By the construction hereinbefore described we are enabled to provide a means whereby hay, straw, or other light produce may be securely loaded and held within the frame; and the construction of the parts is such that when not in use they may be folded, so as to occupy but a small space.
- 15 Having thus described our invention, what we claim as new, and desire to secure by Letters Patent, is—
- 20 1. In a hay-frame, the front standard, C, provided with a vertical slot and cross-bar, in combination with the binder-pole having a hook at its front end, and provided at its rear end with ropes H H, which pass over pulleys 25 attached to the rear cross-bar of the rack, substantially as shown.
2. A binder-pole for hay-racks, made in two

or more sections, and provided at its front end with a hook and at the joints with links F, and hooks f, located on the upper edge of the pole, 30 substantially as shown.

3. The clamp G, adapted for use in connection with the hay-rack and frame, as described, consisting of two members pivoted to each other, and provided with a wedge-shaped portion, and binding-link k, adapted to be clamped upon the binder-pole, and provided with eyes for the reception of the ends of the ropes H.

4. In a hay-rack, the combination of the front post, C, side racks, B B, having pulleys b, the binder-pole, and clamp G, adapted to be secured to the binder-pole, and provided at its lower end with ropes H, which pass over the pulleys b, secured to the side rack, the parts being organized substantially as shown, 45 and for the purpose set forth.

In testimony whereof we affix our signatures in presence of two witnesses.

CHARLES AUGUSTUS PEASLEY.
ISAAC F. DODGE.
